UNITED STATES PATENT OFFICE

100,444

DESIGN FOR A FLASK SUPPORT

Paul H. Sherrick, Chicago, Ill., assignor to E. H. Sargent & Co., Chicago, Ill., a corporation of Illinois

Application May 15, 1936, Serial No. 62,649

Term of patent 7 years

To all whom it may concern:

Be it known that I, Paul H. Sherrick, a citizen of the United States, residing at Chicago, in the county of Cook and State of Illinois, have invented a new, original, and ornamental Design for a Flask Support, of which the following is a specification, reference being had to the accompanying drawing, forming part thereof.

The figure is a perspective view of a flask support showing my new design.

I claim:

The ornamental design for a flask support as shown.

PAUL H. SHERICK.
